UNITED STATES PATENT OFFICE.

WALLACE L. BEMIS, OF BROCKTON, MASSACHUSETTS.

EYEGLASSES.

No. 880,002.

Specification of Letters Patent.

Patented Feb. 25, 1908.

Application filed August 1, 1907. Serial No. 386,593.

To all whom it may concern:

Be it known that I, WALLACE L. BEMIS, a citizen of the United States, residing at Brockton, in the county of Plymouth and State of Massachusetts, have invented certain new and useful Improvements in Eye-glasses, of which the following is a specification, reference being had to the accompanying drawing.

10 My invention relates to improvements in eyeglasses and particularly to improvements in the spring portion thereof; and an object of my invention is to provide an eyeglass spring which will allow of the ready adjustment of the lenses towards and from each other, the ready adjustment of the bridge or bow part of the spring to the nose of the wearer without any sacrifice of the resiliency of the spring, and the use of a short stud, 20 the latter being particularly advantageous where the pupillary distance is short.

It has been found that where the bridge or bow portion of the spring is formed into helical coils at its ends, it is impossible to adjust the bridge part to the nose of the wearer without great sacrifice of the resiliency of the spring; and the form of these helical coils makes it impossible to move the bridge part in adjustment any substantial distance without so deforming the coil as to make it lose its resiliency. Again, where the coils are in the form of a cylindrical helix, the stud must be long in order to carry the lowermost coil away from the convex portion of the lens 35 at the inner end of its horizontal axis; and as is well known to all skilled in this art, the use of a long stud is most objectionable in those cases where the pupillary distance is narrow.

40 In the drawings illustrating the principle of my invention and the best mode now known to me of applying that principle, Figure 1 is a plan view of a pair of eyeglasses fitted with my new spring; Fig. 2 is a section on line A—A of Fig. 1; Fig. 3 is a perspective view of my new spring and Fig. 4 is a front view of a pair of eyeglasses fitted with my new spring, one stud being shown in section.

To each lens *a* is secured a strap *b* provided 50 with the usual stud *c* in which is secured a nose-guard *d* by means of the screw *e*. The latter also secures the end *f* of the spring in the stud. The bridge or bow part *g* of the spring is shaped to fit the nose of the wearer 55 of the glasses, and its ends are bent to form a turn or coil *h* of a cylindrical helix. The

lower end of the coil *h* is now extended to the rear and then to the front to form an elongated coil or loop *i*, the front end of which is bent inwardly and then downwardly, terminating in the portion *j* heretofore referred to. The elongated loop permits the lenses *a* to be moved toward and from each other without any sacrifice of resiliency or spring action in the coil. Further, where the bridge *g* must be moved a substantial distance, as in case 60 there is a hump upon the wearer's nose, the bridge part *g* may be fitted to such a nose by bending the portion *j* of the elongated coil *i* about the point *k*, (as is indicated by the dotted lines in Fig. 2). It will be obvious to 65 all skilled in this art that the spring will lose none of its resiliency by such movement of the part *j*; whereas, when the coils of a cylindrical helix are extended to adjust the 70 bridge part, the helix is deformed and loses 75 its spring action.

It will be noted that the side *m* of the elongated coil lies well within the outside *n* of the coil *h*. This permits the use of a shorter 80 stud; for, the wider coil *h* is raised up where the curved edge of the glasses recede from the coil; and were two similar coils *h* used, it is obvious that the convex edge *o* of the 85 glasses would strike the lower coil and require the use of a longer stud than is necessary with the elongated loop *i*, which allows an interval *p* between its outer side *m* and the opposite curved edge *o* of the glasses and thereby permits the use of a shorter stud. 90

It will be obvious to all skilled in this art that lowering the lenses *a* will be equivalent to raising the bridge part *g*, the object being to alter the relative position of the bridge part *g* and the lenses. 95

I claim:

1. In eyeglasses, an eyeglass spring having a bow part shaped to fit the nose of the wearer; the ends of said bow part being each wound into a turn of a helical coil and then 100 into an elongated loop which extends to the rear of said coil; said bow part and helical turn being susceptible of being raised and lowered about the rear bend of said elongated loop for adjustment of the bow part without 105 deformation of said turn or change of relative position of said bow part and turn.

2. In eyeglasses, an eyeglass spring having a bow part shaped to fit the nose of the wearer; the ends of said bow part being each 110 wound into a turn of a helical coil and then into an elongated loop which extends to the

rear of said coil; the outside of said loop lying well within the outside of said coil and said bow part and helical turn being susceptible of being raised and lowered about the rear bend of said elongated loop for adjustment of the bow part without deformation of said turn or change of relative position of said bow part and turn.

In witness whereof I have hereunto set my hand at said Brockton this twenty-fifth day of July, 1907, in the presence of the two undersigned witnesses.

WALLACE L. BEMIS.
